UNITED STATES PATENT OFFICE.

ALF B. ANDERSEN, OF BROOKLYN, NEW YORK, ASSIGNOR TO ALF B. ANDERSEN & STARR, INC., OF NEW YORK, N. Y., A CORPORATION OF NEW YORK.

DESIGN FOR A BOOK END.

Application filed June 14, 1928. Serial No. 27,117. Term of patent 7 years.

To all whom it may concern:

Be it known that I, ALF B. ANDERSEN, a Norwegian subject, and a resident of the borough of Brooklyn, city of New York, county of Kings, and State of New York, have invented a new, original, and ornamental Design for Book Ends, of which the following is a specification, reference being had to the accompanying drawing, forming a part thereof.

The figure of said drawing is a perspective view of a book end showing by new design.

I claim:

The ornamental design for a book end, as shown.

ALF B. ANDERSEN,
